UNITED STATES PATENT OFFICE.

HERMANN JAWORSKI, OF NEW HAVEN, CONNECTICUT, ASSIGNOR TO
SARGENT & CO., OF SAME PLACE.

DESIGN FOR THE ORNAMENTATION OF HARDWARE.

SPECIFICATION forming part of Design No. 16,205, dated August 18, 1885.

Application filed March 23, 1885. Term of patent 14 years.

To all whom it may concern:

Be it known that I, HERMANN JAWORSKI, of New Haven, in the county of New Haven and State of Connecticut, have invented a new Design for the Ornamentation of Hardware; and I do hereby declare the following, when taken in connection with accompanying drawings and the letters of reference marked thereon, to be a full, clear, and exact description of the same, and which said drawings constitute part of this specification, and represent, in—

Figure 1, a face view of a hinge-plate, showing the ornamentation; Fig. 2, a transverse section of the same.

This invention relates to a design for the ornamentation of various articles of hardware, such as hinges, lock-fronts, knobs, latch-plates, and the various articles of hardware adapted for building purposes, and where a uniformity of style is required, as for a particular building or for a particular room; and the design consists in the representation of a mosaic ground with the representation of single or individual flowers scattered upon the surface and as lying thereon, as shown in the accompanying illustrations.

In the illustrations I show a hinge plate,

which will be sufficient for the purpose of defining the design and its adaptation to the various articles of hardware. The ground represents flat mosaic work, and on the surface of the mosaic ground is the representation of single or individual flowers raised above the surface, as seen in Fig. 2, and appearing to lie thereon.

I do not claim as my design raised figures upon a ground, the essential feature of my design being the representation of mosaic work—that is, giving it the appearance as made up of irregularly-shaped blocks—and the representation of flowers as lying thereon—that is, projecting from the surface.

I claim—

The herein-described design for the ornamentation of hardware, consisting of the representation of the mosaic ground with the representation of individual flowers lying thereon and projecting from the ground, as shown in the accompanying illustrations.

HERMANN JAWORSKI.
